SPEED CONTROL MECHANISM FOR
AUTOMOBILES

Sebastian B. Doyle, Miami, Fla.

Application May 25, 1950, Serial No. 164,210

7 Claims. (Cl. 137—479)

1

The present invention relates to mechanism for controlling the maximum speed of an internal combustion engine, and is more particularly directed to mechanism adapted to regulate the rate of flow of fuel-air mixture to the intake manifold, so that a motor vehicle cannot be driven at a greater speed than a predetermined indicated speed.

A principal object of the present invention is to provide a governor for an automotive vehicle, which is sensitive and accurate in operation responsive to the suction pressure of the intake manifold, said governor having a relatively few moving parts, thus reducing wear and need for adjustments to an absolute minimum.

A further object of the present invention is to provide a speed governing mechanism for an internal combustion engine having a conical shaped internal flow chamber which is completely housed within the intake manifold making the mechanism tamper proof and adaptable to fit the many different makes of automotive vehicles.

A further object of the present invention is to provide a simplified and improved adjustable governor for an automotive vehicle.

Another object of the present invention is to provide a speed control mechanism for an automotive vehicle which operates smoothly without surging and is consequently accurate in operation for a relatively long period of time, keeping at a minimum the need for repairs and adjustment.

A still further object of the present invention is to provide a governor in an automotive vehicle that will completely close off all flow of fuel air mixture if on descending a hill the motor is driven sufficiently by the accelerating vehicle, and opens up as the speed decreases the slightest amount, thus resulting in a considerable braking action and saving of fuel from the closed off engine intake.

With these and other objects in view, the invention will be best understood from a consideration of the following detailed description taken in connection with the accompanying drawings, forming a part of the present specification with the understanding, however, that the invention is not confined to any strict conformity with the showing of the drawings, but may be changed or modified so long as such changes or modifications mark no material departure from the salient features of the invention as expressed in the appended claims.

In the drawings:

Figure 1 is a cross sectional view in elevation of my invention in its normal operating position

2

between the carburetor and the intake manifold.

Figure 2 is a cross sectional view of a modification of my invention.

Figure 3 is a cross sectional view of a further modification of my invention.

Referring to the drawings and more particularly to the invention shown by Figure 1, the numeral 1 indicates generally the body of the governor which is positioned between the mixing chamber of a carburetor 2 and the intake manifold 3. Gaskets 9, 9 are placed between the governor 1 and the carburetor 2 and intake manifold 3 so that when the nuts 5, 5 are tightened on the studs 4, 4 the complete assembly becomes air tight. One of the studs 4 is provided with a hole 6 which when made to align with a similar hole which extends thru the side wall of the governor permits a sealing wire 8 to be threaded therethru, and a seal 7 secured to the ends of 10 the wire 8. As is hereinafter explained in more detail, it can be seen that the operating mechanism of the governor 1 is situated completely within the intake manifold 3 and so cannot be tampered with or adjusted without having to 20 break the seal 7, pull out the wire 8 and remove the governor 1 from its operating position. In order to adapt the governor to many different makes of automobiles that have different sized intake manifolds the bores 4a, 4a are made elliptical in shape and larger in diameter than the diameter of the studs 4, 4.

Centrally disposed within the governor 1 is a fluid passageway having a conical cross section to form a circular tapering wall 10. At the lower end of the wall 10 there extends a yoke 11 having a centrally disposed threaded bore 12 adapted to receive a threaded bushing 13 which is locked into place by a lock nut 14. Slidably mounted in the bushing 13 and extending upwardly therefrom is a valve stem 15 on the free end of which is mounted a valve head 16. The valve head 16 may be of any shape or configuration, such as a ball type valve, or a disk having elliptical shape, etc., so long as the results obtained thereby are substantially the same as those obtained by the circular valve head 16. A conical compression spring 17 encircles the valve stem 15 and extends between the valve plate 16 and the bushing 12. The lower end of the valve stem 15 is provided with threads to receive a nut 18 and a cotter pin 19. The valve stem 15 may be provided with a plurality of bores to receive the cotter pin 19 at various positions of the nut 18 thus permitting the spring tension of the spring 17 to be adjusted.

In the assembling of the device, the bushing

13 is threaded in the yoke 11, so that its upper end extends beyond the upper wall of the base of the yoke 11. The free end of the valve stem 15 with the conical spring 17 encircling same, is permitted to be placed in the bore of the bushing 12 and pushed downwardly until the free end of the stem 17 extends beyond the bushing 13 whereupon a nut 18 is threaded thereon. The conical spring 17 is now firmly held in position at the upper end by the valve head 16 and at the lower end by the upper end of the bushing 13. The cotter pin 19 is now inserted thru the valve stem 15 to lock the nut 18 in place. Since the valve head 16 is fixed in area and the side wall 10 of the governor is tapered, there is a fixed, but different volume rate of flow of air fuel mixture for each position of the valve head 16. In fact the volume rate of flow decreases as the valve head 16 moves downwardly.

By selecting the speed at which it is desired that the governor is to operate, the suction pressure and the rate of flow of fuel-air mixture will be known. This designated pressure is then manually applied on the valve head 16 and the distance that the valve head 16 moved downwardly is measured. The bushing 13 is then threaded upwardly or downwardly as the case may be until the valve head 16 is placed at a position equal to the distance just measured, above the position at which the rate of volume flow of air-fuel is equal to that flow that will take place at the designated speed. The lock nut 14 is then tightened against the yoke 11 to prevent the bushing 13 from turning out of its already calibrated position. However, if it is desired to change the speed at which the governor is to operate or control, the lock nut 14 is first loosened and the bushing 13 threaded upwardly or unthreaded depending on whether it is desired that the maximum speed be increased or decreased, respectively, and the lock nut 14 again tightened against the yoke 11.

Now, as the speed of the engine is increased from the idling position, the suction pressure becomes increased, thus causing the valve head 16 to move downwardly against the spring pressure 17. As long as the engine speed is less than the speed at which the governor is set for, the clearance between the edge of the valve head 16 and the side wall 10 of the governor body is sufficient to allow an unimpeded flow of the air fuel mixture from the carburetor 2 to the intake manifold 3. As soon as the maximum speed to which the governor is set is reached, the valve head 16 will be in truth floating at a position where the rate of volume flow of air fuel mixture permitted to flow past the valve head is equal to the maximum amount of fuel air mixture required to maintain the designated speed. Any attempt to increase the speed beyond this maximum speed will not result in any increase in fuel air mixture since any increase in suction pressure would cause the valve head 16 to move downwardly and decrease the rate of flow of fuel air mixture. In Figure 1, the full lines indicate the valve 16 in a non-operating position, while the dotted lines indicate the position of the valve 16 at the maximum desired engine speed. In the event that extremely high suction pressures are created, the valve head 16 will be caused to move downwardly until the side walls 16a of the valve head 16 seat themselves on the tapering walls 10 of the governor so as to cut off all fuel air mixture flow to the intake manifold 3. This condition can be caused by accelerating downhill at an excessively high

speed. The high speed being travelled will cause a very high suction pressure which in turn will cause the valve head 16 to move downwardly until it seats itself on the side wall 10.

5 The governor 20 illustrated in Figure 2, shows the identical construction as the device of Figure 1 with the addition of a valve seat 22 to permit the valve head 21 to seat thereupon when the previously described condition occurred wherein 10 abnormally high suction pressures are created. Upon release of the high suction pressure, the 15 spring pressure 23 will cause the valve head 21 to return to its normal operating position 21 (shown on dotted line) or perhaps to a higher position depending on the speed then being attained.

Figure 3 shows a further modification of the invention. In this device the inside wall of the governor 30 is cylindrical in shape in the upper portion thereof, as at 31 and conical in shape in 20 the lower portion of the governor as at 32. A valve seat 33 is likewise provided. In the operation of the governor 30, while the valve head (not shown) is moving within the confines of the upper portion of the governor 30, the rate of flow of air-fuel mixture permitted will be constant, but as 25 the suction pressure increases and the valve head moves downwardly within the lower half of the governor 30, the rate of flow of air-fuel mixture will be decreased in the same manner as in the 30 governors 1 and 20 of Figures 1 and 2 respectively. This type governor 30 is utilized in those instances 35 where it is most desirable to permit an unimpeded flow of fuel air mixture until a speed is reached which is near the maximum speed at which the governor is set; at which time, the valve plate will be moving downwardly out of the upper cylindrical chambers 31 into the lower conical chamber 32 to control the volume flow of fuel air mixture.

40 Having now disclosed my invention and realizing that, in view of my disclosure many modifications in details of construction or design will readily occur to those skilled in the art, I do not choose to limit myself except as in the appended claims.

45 What I claim is:

1. A device of the class described comprising a body member, a fluid passageway axially disposed in said body member, said passageway having tapering walls in a direction toward one end of said body member, valve support means mounted at said one end of said body member, a bore in said valve support means, a bushing mounted in said bore, a valve slidably mounted in said bushing and having a valve head positioned at the other end of said body member in said fluid passageway, resilient means positioned between said valve head and said bushing adapted to yieldingly maintain said valve head in said other end, locking means for securing said bushing in position, and stop means mounted at the free end of said valve.

2. The structure as recited by claim 1 and a valve seat mounted at said lower end of said body member.

3. A governor comprising a body member, a chamber axially disposed within said body member, a yoke mounted at the lower end of said body member, a bore contained by said yoke in axial alignment with said chamber, a bushing mounted in said bore, a valve stem slidably mounted in said bushing, a valve mounted on said stem and positioned in said chamber at the upper end thereof, resilient means encircling said stem and positioned between said valve and said bush-

ing adapted to maintain said valve in said upper end of said body member, means contained by said chamber adapted to coact with said valve whereby upon actuation of said valve the flow of fluid through said chamber is decreased, and stop means mounted at the free end of said valve stem adapted to limit the movement of said valve.

4. The structure recited by claim 3 wherein said chamber means consists of a decreasing cross sectional area in a direction toward said lower end of said body member.

5. The structure recited by claim 3 wherein said chamber means consists of a cross section of constant area in the upper portion thereof, and a cross section of decreasing area in the lower section.

6. In a speed control mechanism for internal combustion engines having a body member adapted to be secured between a carburetor and an intake manifold, the combination of a fluid passageway axially disposed within said body member, said passageway being of decreasing cross sectional area in a direction toward the lower end of said body member, a yoke secured at said lower end, a bore contained in said yoke, 25 a bushing threadedly mounted in said bore in axial alignment with said fluid passageway, a valve stem slidably mounted in said bushing, a valve mounted on said valve stem, a conical spring member interposed between said valve and said bushing and encircling said valve stem, lock nut threadedly mounted on said bushing adjacent said yoke and a nut threadedly secured to the free end of said valve stem.

7. A governor comprising a body member, a 35 chamber disposed in said body member, said

chamber having tapering side walls, a yoke mounted on said body member, a bore contained by said yoke, a spring support member mounted in said bore, a bore contained by said spring support member, a valve stem slidably mounted in said bore of said spring support member and extending into said chamber, a valve head mounted on one end of said valve stem, spring means mounted between said valve head and said spring support member, means for adjusting said spring means, said spring adjusting means being mounted on the other end of said valve stem and adapted to limit the movement of said valve head, and means contained by said spring support member adapted to vary the position of said valve head in said chamber without changing the force exerted by said spring means on said valve head.
